Attorney.*

UNITED STATES PATENT OFFICE

HIRAM TEATER, OF CLEVELAND, OHIO

COKING RETORT

Application filed November 19, 1927. Serial No. 234,509.

The invention relates to improvements in coking retorts for the destructive distillation of coal as described in the present specification and shown in the accompanying drawings which form part of the same.

The invention appertains to a coking retort for treating coal in two distinctive steps or stages, the first being the subjecting of the coal to an external application of heat in order to drive off the gaseous and vaporous products, the second being the injection or diffusion of superheated steam throughout the coal in order to complete the coking process.

15 The invention has for its object primarily to provide an efficient coking retort of the type described, one which will facilitate and expedite the distillation of coal: more particularly the invention comprehends a digester embodying a band like coal chamber for the purpose of holding a thin vertical wall of coal which is surrounded both on the outside and inside and also on the top with superheating chambers whereby a maximum of 20 heating surface is obtained for a given mass of coal resulting in a more thorough and complete coal distillation.

With these and other objects in view, the invention consists of the novel construction and arrangement of a coking retort as described in the present specification, shown in the accompanying drawings and claimed in the claims hereinafter appended.

Referring to the drawings: Figure 1 is a 35 plan view of the coking retort.

Figure 2 is a vertical elevation thereof.

Figure 3 is a transverse sectional view taken on the line 3—3 of Figure 2.

Figure 4 is a vertical sectional view taken 40 of the line 4—4 of Figure 1.

Figure 5 is a fragmentary view of the lower portion of the coking retort viewed endwise and showing the particular construction of the drop bottom.

45 Like numerals of reference indicate corresponding parts in each of the figures throughout the drawings.

In the drawings, the coking retort takes the form of a rectangular shaped member in elevation which in cross section is comparative-

ly narrow and has its ends rounded off in semi-circles as clearly seen in Figures 1 and 3. The coking retort is provided with an outside shell or wall 10, an intermediate wall 11, and an inner wall 12, which provide an intermediate vertical coal chamber 13 surrounded by an outside superheating chamber 14 and an inside superheating chamber 15. The outside steam chamber communicates with the space 16 provided between a double walled top but is isolated from the intermediate and inner chambers. 55

The coal chamber has a drop bottom 17 which will be hereinafter more fully described. The inner chamber 15 is isolated from the other chambers and is divided into two parts by a longitudinal baffle 18. This baffle assists in strengthening the inner steam chamber 15 in addition to functioning to provide double compartments whereby steam 60 may enter one and then pass into the other. The coal chamber is rigidly braced to the outer shell or wall 10 by means of a plurality of spacers 19 consisting of short bars having their ends rigidly secured to walls 10 and 11. 65

In the vicinity of the top of the coking retort 20 and on each side is a charging door 21 of conventional design, which charging door leads into the coal chambers as at 22 and is isolated from the outer steam chamber 14. 70 Similarly, on each side of the coking retort and preferably at the same height as the charging doors is an egress 23 which connects with piping leading to the apparatus for the fractionation of the volatile matter driven off from the coal. These passages for the outlet or by-products are likewise isolated from the chamber 14 as at 24 Figure 3. 75

Superheated steam is piped to the outer chamber 14 through a valve-controlled pipe 25 which communicates with this steam chamber in the vicinity of its bottom and at one side thereof. The superheated steam circulates around this chamber and passes out of a pipe 26 on the opposite side thereof. Superheated steam is piped to one division of the inner chamber through a pipe 27 which passes vertically downwardly through the top of the coking retort and extends downwardly through the inner chamber 15 on one side of 80 85 90 95 100

the baffle 18 and terminates short of the bottom 28 of this chamber. Superheated steam having circulated on this side or compartment of the inner chamber passes through a plurality of apertures 29 provided in the lower end of the baffle 18 to the other half or compartment of this inner chamber and is conducted from there through a pipe 30 leading outside of the coking retort. A distinctive advantage of having the pipes 27 and 30 extend to the vicinity of the bottom of the chamber is that they can be used to siphon off water resultant from the condensation of the steam incidental to the operation of the coking retort.

In order to diffuse superheated steam into the coal in the second step, downwardly extending perforated pipes 31 are supplied, there being preferably six in number as shown in the accompanying drawings, which 20 pipes extend through the top of the coking retort and are isolated from the superheating chambers. In order to eject the residual mass after completion of the coking process a ram is provided which consists of a ram proper 32 slidable vertically in the coal chamber and connected to rods 33, four in number, which extend externally of the coking retort for attachment to hydraulic cylinders or other operating means which are conventional to the art.

The drop bottom 17 consists of a door provided with a circumferential flange 34 beveled as at 35 for the purpose of abutting an oppositely beveled edge of the bottom of the coal chamber opening. This engagement of the beveled edges provides a very efficient seal against leakage of the products distilled from the coal. The door is hinged at one end as at 35' and is secured when closed by means of locking devices 36 which locking devices consist of lugs 37 rigidly projecting from the shell of the coking retort and carrying yokes 38 which are pivoted at 39 in order that they may swing outwardly. These yokes are disposed to slip over arms 39' integrally projecting from the sides of the door. Each yoke carries a setscrew 40 on its free end which is tightened for the purpose of bearing against the arm 39' so as to press the door firmly against the bottom of the coking retort. To drop the door it is merely necessary to slacken the setscrew 40, swing the yoke 38 outwardly from the door so as to free it from engagement with the arm 39' which allows the door to drop.

Having now described the preferred form of the embodiment of the invention capable of carrying the same into practical operation, it is distinctly understood that such changes and modifications may be resorted to as may fairly come within the spirit and scope of the invention and claims hereinafter following.

What I claim is:

1. A sheet metal coking retort, composed

of an outer vertical wall, an inner vertical wall within said outer vertical wall and an intermediate vertical wall between said outer vertical wall and said inner vertical wall, each of the walls being spaced horizontally from each of the other walls and said outer vertical wall extending above the tops of both of the other walls, each of the walls being annular in horizontal cross section, a bottom member joining the lower extremities of the outer and intermediate walls, a bottom member closing the lower extremity of the inner wall, an outer top member closing the upper extremity of the outer wall, an inner top member spaced therefrom and closing the upper extremities of the intermediate and inner walls, and spacers rigidly extending between the outer and intermediate walls whereby an annular coal chamber is formed between said inner vertical wall and said intermediate vertical wall that is entirely confined by heating surfaces with the exception of an open bottom.

2. A sheet metal retort, composed of an outer vertical wall, an inner vertical wall within said outer vertical wall and an intermediate vertical wall between said outer vertical wall and said inner vertical wall, each of the walls being spaced horizontally from each of the other walls and said outer vertical wall extending above the tops of both of the other walls, each of the walls being of a horizontally elongated annular shape in horizontal cross section, a bottom member joining the lower extremities of the outer and intermediate walls, a bottom member closing the lower extremity of the inner wall, an outer top member closing the upper extremity of the outer wall, an inner top member spaced therefrom and closing the upper extremities of the intermediate and inner walls whereby an annular coal chamber is formed between said inner vertical wall and said intermediate vertical wall that is entirely confined by chambers with the exception of an open bottom, a coal charging entrance for said coal chamber located on each of two opposite sides of the coking retort, and an egress for volatile matter from said coal chamber also located on each of two opposite sides thereof.

Signed at Cleveland, Ohio, the 8th day of November, 1927.
